UNITED STATES PATENT OFFICE.

WM. T. SLOCUM, OF PHILADELPHIA, PENNSYLVANIA, ASSIGNOR TO JAMES S. MASON & CO., OF SAME PLACE.

IMPROVEMENT IN THE MANUFACTURE OF METAL BOXES.

Specification forming part of Letters Patent No. 47,606, dated May 2, 1865.

To all whom it may concern:

Be it known that I, WILLIAM T. SLOCUM, of Philadelphia, Pennsylvania, have invented an Improvement in the Manufacture of Metal Boxes; and I do hereby declare the following to be a full, clear, and exact description of the same, reference being had to the accompanying drawings, and to the letters of reference marked thereon.

My invention consists in the manner, described hereinafter, of securing together the two ends of a strip of tin, so that the same may be used for the side of a box such as is used for containing blacking and other materials.

In order to enable others to make and use my invention, I will now proceed to describe the manner of carrying it into effect.

On reference to the accompanying drawings, which form a part of this specification, Figure 1 represents a strip of tin to be formed into the side of the box; Fig. 2, a sectional view showing the strip as bent, preparatory to the fastening together of the ends; Fig. 3, the same with the ends secured together, and Fig. 4 a perspective view showing the form of the two ends of the strip.

Similar letters refer to similar parts throughout the several views.

A is a strip of tin, the width of which is equal to the height of the box intended to be made, and the length of which is such that when the ends are secured together it will form a circle of the desired diameter of the box. One end of the strip is cut away to a point on

each side, so as to form a lip, *a*. This pointed end is bent upward. In this end of the strip is also made a triangular orifice, *x*, the metal partly punched from the strip in forming this orifice being turned upward, as shown in Fig. 4, and presenting an angular lip, *a'*, parallel to the lip *a*. In the opposite end of the strip are two transverse slots, *e e'*, into which the said lips *a a'* are fitted after the strip of tin has been bent in the form of a circle, as seen in Fig. 3, after which the lips are bent down in contrary directions, and the joint thus formed is completed by a sharp blow with a hammer or mallet. It will be apparent that the strip may be readily cut to the shape necessary to form the desired joint without the aid of complicated and expensive machinery, and that the joint is simple, effective, and may be made secure without the aid of solder or rivets.

I claim as my invention and desire to secure by Letters Patent—

Connecting together the ends of a strip, A, by inserting the lips *a a'* at one end of the strip through the slots *e e'* at the opposite end, and bending them down against the inner side of the slotted end when the said lips and slots are formed, substantially as described.

In testimony whereof I have signed my name to this specification in the presence of two subscribing witnesses.

WM. T. SLOCUM.
